UNITED STATES PATENT OFFICE.

EMIL PEYER, OF WANGEN, SWITZERLAND, ASSIGNOR TO FIRM WALDER & CO., OF BRUTTISELLEN, CANTON ZURICH, SWITZERLAND.

MACHINE FOR ATTACHING HEELS TO BOOTS AND SHOES.

1,403,104.

Specification of Letters Patent. Patented Jan. 10, 1922.

Application filed March 25, 1920. Serial No. 363,793.

To all whom it may concern:

Be it known that I, EMIL PEYER, a citizen of the Swiss Confederation, residing at Wangen, Canton Zurich, Switzerland, have 5 invented certain new and useful Improvements in and Applicable to Machines for Attaching Heels to Boots and Shoes, of which the following is a specification.

The present invention relates to improvements in and applicable to machines used 10 for attaching heels to boots and shoes from the inside of the same, and has for its object the construction of a heel nailing appliance by which all the nails for a heel may be 15 driven in simultaneously at the same or different inclinations to the heel and to each other, whereby the heel and its pieces are held together and to the boot or shoe by inclined nails which may be inclined by 20 relation to the outer shape of the heel.

The object of the invention is to provide 25 an appliance of the kind described which may be easily inserted in the boot or shoe, without distorting its shape and a further 30 object of the invention consists in forming said appliance or nail block and its constituent parts in such a manner that the 35 nails may be driven in the heels at the very periphery thereof thus securing a good and firm connection of the parts.

The invention further consists of details 40 of construction, which together with the features first mentioned, will be better understood by reference to the drawings, in 45 which—

Fig. 1 is a sectional elevation of the nail 50 block together with part of a boot with heel to be attached.

Fig. 2 is a section taken on line A—B of 55 Fig. 1 the boot being shown in dotted lines.

Figs. 3 and 4 are cross-sections on lines 60 C—D and E—F of Figs. 2 and 1 respectively viewed in the direction of the arrows.

Fig. 5 is a top view of the nail block.

The nail block according to the construction shown in the drawings by way of an example comprises a rod 1 carrying a head 2. The latter is composed of three super- 65 posed pieces firmly fixed together. The head 2 has seven holes 3 each adapted to receive a nail 6 and a flexible nail driver 7.

All the drivers 7 are fastened on a slide 8 which is slidably mounted on the rod 1. To

guide the slide 8 a pin 10 is provided on 55 the head 2 projecting into a bore 11 of the slide 8. The slide 8 is moved up and down by any suitable device not shown in the drawing and a sleeve 12 is fastened to the head 2 overbridging the gap between the 60 head 2 and the slide 8. Each driver 7 consists of a closely wound steel wire and loosely fits the bore 3 in such manner that it may move in said bore without undue friction. Each bore 3 consists of three parts set at 65 angles to each other, each part is straight and the length of the uppermost part 3^a is equal to or greater than the length of a nail 6 to be driven in the heel 4 of the boot 5. The angles at which the bores 3^a are 70 drilled are varied according to the inclination desired to be given to the nail to be driven such inclination being determined by the shape of the heel. It will be seen from the drawings that owing to the particular 75 shape of the head 2 and of the bores 3 in it and by the employment of the flexible drivers 7 the head 2 may be placed well within the hind end of the boot and nails 6 may be driven in the heel from very near 80 the hind end of the heel thus giving the latter a good hold and forming a close joint.

When the nail block is being used the slide 8 is lowered and therewith the drivers 7 so that the nails 6 can be placed in the 85 bores 3^a of the head 2. The boot 5 and the heel 4 to be attached are placed in position on the nail block and the whole is moved under the cross-head of the machine. The slide 8 is moved upwards in the direction 90 of the arrow I whereby the nails are forced out of the head 2 into the heel 4 by the drivers 7.

The number, position and inclination of the holes may be varied according to the 95 requirements of the heel and of the shape thereof.

While I have described what I believe to be the best mode of carrying my invention into commercial use, I do not confine myself 100 to the details, as they may be modified without departing from the spirit of the invention.

Having now described my invention, what I claim as new, and desire to secure by Letters Patent, is—

A machine by which all nails for attaching a heel to a boot may be simultaneously

driven into the heel at angles to each other and to the heel comprising in combination a head having a plurality of bores, the parts of each bore being at an angle to each other, 5 the uppermost portion of each bore being adapted to receive a nail, a closely coiled steel wire driver in each of said bores, and a slide movable on a rod carrying said head

on which the said drivers are mounted substantially as described.

In testimony whereof I affix my signature in presence of two witnesses.

EMIL PEYER.
